UNITED STATES PATENT OFFICE.

HENRY J. BUCKEL, OF MISHAWAKA, INDIANA.

SEGMENT-MITERING MACHINE.

No. 856,842.

Specification of Letters Patent.

Patented June 11, 1907.

Application filed February 14, 1907. Serial No. 357,302.

To all whom it may concern:

Be it known that I, HENRY J. BUCKEL, a citizen of the United States, residing at Mishawaka, in the county of St. Joseph and 5 State of Indiana, have invented new and useful Improvements in Segment-Mitering Machines, of which the following is a specification.

This invention relates to wood working 10 machines of that class which are employed for mitering the ends of segments, to be used in the construction of rims of wheels, and for other purposes.

The invention has for its objects to construct a machine of the class referred to 15 which may be used for operating upon segments of various sizes, and which may be readily set or adjusted to cut the mitering ends of the segments at various angles.

20 A further object of the invention is to construct a machine of this class, the capacity for work of which shall be practically unlimited except by the speed at which it may be driven.

25 Further objects of the invention are to simplify and improve the construction and operation of this class of machines.

With these and other ends in view which 30 will readily appear as the nature of the invention is better understood, the same consists in the improved construction and novel arrangement and combination of parts which will be hereinafter fully described and particularly pointed out in the claims.

35 In the accompanying drawings has been illustrated a simple and preferred form of the invention; it being, however, understood that no limitation is necessarily made to the precise structural details therein exhibited, 40 but that changes, alterations and modifications within the scope of the invention may be resorted to when desired.

In the drawings, Figure 1 is a side elevation 45 of a machine constructed in accordance with the principles of the invention. Fig. 2 is a side elevation of the machine seen from the opposite side. Fig. 3 is a transverse sectional view taken on the plane indicated by the line 3—3 in Fig. 1. Fig. 4 is a sectional 50 detail view on a somewhat longer scale taken substantially on the plane indicated by the line 4—4 in Fig. 1. Fig. 5 is a detail view, in elevation, of the connecting rods or shafts extending longitudinally through the machine. Fig. 6 is a perspective detail view

showing one of the links of the endless feed chain.

Corresponding parts in the several figures are denoted by like characters of reference.

The machine includes a main or principal 60 frame A which is stationary, and a movable or adjustable frame B. The main frame is provided with bearings for transversely disposed rock shafts 1 and 2 having bell-crank 65 3—3 connected by a link or connecting rod 4 whereby motion is transmitted between the rock shafts so that the latter will rock in unison. The rock shafts 1 and 2 are provided with radially extending arms 5 that are pivotally connected with brackets 6, 70 which latter form parts of the frame structure B. The latter, as will be seen, is thus supported by the rock shafts 1 and 2, in such a manner that vertical adjustment of the entire frame structure B may be effected by 75 oscillating the rock shafts in their bearings. The rock shafts 1 and 2 are provided with arms 7 carrying weights 8 whereby the frame structure B and its related parts will be counterpoised so that vertical adjustment 80 thereof may be effected without strenuous exertion on the part of the operator, the adjustment being effected by means of a hand-lever 9 connected with the rock shaft 1 which is located at the front end or feed end of the 85 frame of the machine where the attendant is stationed when the machine is in operation. For the purpose of securing the frame structure B at the desired adjustment, the hand-lever 9 is provided with a stud 10 guided in a 90 segmental slot 11 in a bracket 12 equipped with a tail nut 13 which may be tightened against said bracket. A suitable gage or indicator 14 is also provided which in practice will be inscribed with a scale that serves 95 to indicate to the operator the precise point of adjustment of the frame B.

The main shaft 15 for driving the machine is supported for rotation in brackets 16 upon the rear end of the main frame A, said shaft 100 being driven from any suitable source of power, in any suitable and convenient manner; for instance, by a belt engaging a band wheel 17 upon said shaft. The frame A is provided with bearings for a countershaft 18 105 having a band wheel 19 which is connected by a belt 20 with the main shaft 15 from which motion, at reduced speed, will thus be transmitted to the countershaft. The band wheel 19 is loosely mounted upon the coun- 110

tershaft 18, but may be connected with the latter, so as to revolve therewith, by means of a clutch 22 of ordinary construction, said clutch being operable by means of a shifting 5 lever 23 fulcrumed upon the main frame at 24 and extending to the front end of the machine within convenient reach of the operator.

The countershaft 18 is provided with links 10 or radius bars 25 supporting a floating shaft 26 carrying a spur wheel 27 meshing with a pinion 28 upon the countershaft from which motion will thus be transmitted, at reduced speed, to the floating shaft 26 in any position 15 occupied by the latter. The floating shaft 26 is connected by means of links 29 with a shaft 30 journaled in suitable bearings upon the vertically adjustable frame B, and the shafts 26 and 30 are provided with sprocket 20 wheels 31 and 32 connected by a link belt 33 whereby motion will be transmitted as will be readily understood.

The shaft 30 is located near the rear end of the frame B, and a corresponding shaft 34 is 25 supported in suitable bearings near the front end of said frame. Said frame is also provided near its front and rear ends with depending brackets 35 and 36 affording bearings for shafts 37 and 38. The shafts 30, 34, 30 37 and 38 carry sprockets 39 over which is guided an endless flexible element consisting of a chain 40 which constitutes the feed device of the machine. The chain 40 is provided at intervals with specially constructed 35 links 41, shown in detail in Fig. 1 of the drawings, said links being provided with transverse flanges 42 upon which cross pieces 43 are bolted or otherwise secured; said cross pieces serving to engage the segments that 40 are to be operated upon for the purpose of pushing or feeding the same past the saws whereby the ends of said segments are trimmed or cut at the requisite angle, as will be hereinafter more fully described. The 45 edges of the links are beveled or dove-tailed as will be seen at 44, and a correspondingly beveled or dove-tailed guide-way 45, best seen in Fig. 4 of the drawings, is formed in the bed of the frame B for the purpose of 50 guiding said links.

The frame B is provided near its front and rear ends, respectively, with transverse dove-tailed grooves 46 and 47 in each of which is guided a pair of oppositely movable slides 55 thus designated respectively 48, 48^a and 49, 49^a. In suitable bearings beneath the transverse grooves 46 and 47 are journaled transverse shafts 50 and 51, each provided with oppositely threaded portions engaging nuts 60 52 that are fitted in recesses 53 in the several slides. The transverse shafts 50 and 51 are provided with bevel pinions 54 meshing with corresponding bevel pinions 55 upon a longitudinally disposed transmission shaft 56 65 whereby motion is transmitted between the

shafts 50 and 51; the former of said shafts is provided with a hand wheel 57 whereby it may be conveniently manipulated for the purpose of effecting simultaneous adjustment of the slides 48, 48^a and 49, 49^a.

Each of the slides 48, 48^a and 49, 49^a carries a vertically movable rod or member 58 having at its lower end an anti-friction member such as a wheel or caster 59. The vertically movable members 58 are provided with 75 heads 60 that are connected in pairs by means of longitudinally disposed rods which I call the track bars 61; these track bars are for the purpose of supporting the segments that are to be operated upon while they are 80 being conveyed from one end of the machine to the other by means of the feed chain. The head 60 upon one of the vertically movable members 58 at one side of the machine also supports an upstanding flange constituting 85 a gage plate 62, clearly seen in Figs. 2 and 4 of the drawings.

The vertically movable members 58 are supported upon a guide by adjusting levers 63 which are fulcrumed, in pairs, adjacent to 90 the transverse shafts 50 and 51, said levers being provided with short arms 64 extending inwardly in the direction of the longitudinal center of the machine, and carrying anti-friction rollers 65 that are in engagement 95 with cams 66 mounted upon the longitudinal shaft 67, by the partial rotation of which the levers 63 will be rocked upon their fulcras, thus raising or lowering the vertically movable members 58, and the bars connected therewith; it being understood that the movement of the levers and the vertically movable members is simultaneous and uniform. The shaft 67 carries pinions 68 meshing with similar pinions 69 upon a longitudinal shaft 70 connected by miter gearing 71 with a transverse shaft 72, the latter carrying at one end a hand-lever 73 whereby it may be conveniently manipulated to effect the desired adjustment of the levers 63, the 100 vertically movable members 58 and related parts.

It will be seen from the foregoing description that by simply manipulating the shaft 50 by means of the hand-lever 57, the slides 115 carrying the vertically movable members 58 may be transversely adjusted, said slides moving in pairs, in opposite directions, thus adjusting the track bars 61 at various distances apart; when this adjustment is being 120 effected, the vertically movable members 58 will travel along the upper surfaces of the adjusting levers 63, which are usually in oppositely inclined positions at the two sides of the machine; by reason of this fact, it is obvious 125 that transverse adjustment of the track bars will at the same time result in a vertical adjustment of said bars; but independent vertical adjustment of the track bars may be effected, when desired, by manipula- 130

tion of the shaft 72 having the hand-wheel 73 whereby, through the intermediate mechanism provided for the purpose, the adjusting levers 63 will be rocked upon their respective 5 fulcrums, thus raising or lowering the vertically movable members 58, and consequently effecting vertical adjustment of the track bars. It is considered to be within the scope of the invention to provide conveniently located gages or scales whereby the exact adjustment of the parts will be visually indicated to the operator, who will thus be enabled to set or adjust the parts with the utmost nicety according to the work that is to 15 be performed.

The trimming or mitering of the ends of the segments is effected by means of a pair of circular saws 74 mounted upon arbors or mandrels 75 which are supported adjustably 20 in oppositely inclined positions at the sides of the machine. The lower, inner ends of the mandrels 75 are journaled in bearings 76 hingedly supported upon the frame B; the outer, upper ends of the mandrels 75 are 25 journaled in sleeves 77 pivotally supported by means of trunnions 78 in forks 79 at the upper ends of vertically adjustable rods 80 that are guided in suitable bearings 81 upon the frame A. The rods 80 are provided with 30 racks 82 engaged by spur wheels 83 upon a shaft 84 journaled transversely in the frame A, said shaft being connected by miter gearing 85 with a vertically disposed shaft 86 which in turn is connected by miter gearing 87 with a longitudinally disposed shaft 88 having at one end a hand wheel 89 whereby it may be conveniently manipulated to effect the desired vertical adjustment of the 35 forked rods 80 whereby the bearings for the outer ends of the saw carrying mandrels are supported. The shaft 84 carries a grooved 40 pulley or drum 90 to which is attached one end of a flexible element such as a cord or cable 91 which, after being wound upon the drum or pulley, is guided over a suitable 45 guide member such as a pulley 92, said flexible element carrying at its free end a weight 93 whereby the saw carrying mandrels are counterpoised so as to facilitate 50 their adjustment by the operator.

It is obvious that within the scope of the invention ordinary well known means may be provided for the purpose of locking the shaft 88 at various adjustments in order to 55 prevent accidental displacement of the saws; it is also obvious that a scale or indicator may be employed for the purpose of visually indicating to the operator the exact pitch or angle to which the saws have been adjusted.

The saw mandrels are provided with pulleys or band wheels 94 which are connected by belts or bands 95 with driving pulleys or band wheels 96 upon the main shaft 15 from which motion will thus be transmitted directly to the saw mandrels; for the purpose 60

of imparting to the belts 95 the requisite twist, to prevent them from slipping from the mandrel pulleys, said belts are guided in contact with cone pulleys 97 idly supported upon a shaft 98.

The vertically adjustable frame B is provided at suitable distances from its front and rear ends with pairs of uprights 99 which are connected, in pairs, by cross-bars 100. The cross-bars are provided with bearings wherein are journaled swivel nuts 101 provided with sprocket wheels 102 which are connected by a link belt 103 whereby said nuts may be rotated in unison; said nuts are also provided with hand wheels 104 whereby they 80 may be conveniently manipulated, for the purpose of effecting simultaneous and uniform vertical adjustment of threaded rods 105 that extend through the nuts. Said threaded rods carry at their lower ends a so-called brush 106 consisting of a back 107 equipped with a plurality of downward projecting flexible resilient tongues 108, the lower extremities of which will thus be adjustably supported a suitable distance above 90 and intermediate of the longitudinally disposed track bars 61.

From the foregoing description taken in connection with the drawings hereto annexed the operation and advantages of this 95 invention will be readily understood to those skilled in the art to which it pertains.

The previously prepared segments or blanks that are to be operated upon, and which in the drawing are designated by the 100 letter S, are placed upon the track bars 61 at the feed end of the machine, where they may be deposited in stacks or bunches, it being only necessary to take care that they are properly placed in contact with the upstanding flange or guide plate 62. It is also obvious that the adjustable parts of the machine, namely, the track bars 61, the saws 74, and the brush 106 must have been previously 105 properly adjusted according to the work that 110 is to be performed. The saws having been set in motion, the feed mechanism is then started by operating the shifting lever 23 to throw the clutch member 22 into engagement with the pulley or band wheel 19 so as 115 to lock the latter upon the countershaft 22; the endless feed chain 40 being thus set in motion, the links of said chain having the cross pieces 43 will engage the blanks or segments and carry the latter along the track 120 bars 61, beneath the brush 100 and past the saws 74, which latter will trim or cut the ends of the segments at the proper angle, the segments or blanks being meanwhile held in position upon the track bars, with sufficient 125 security, by the flexible resilient tongues of the brush member; the latter may be of any desired length, and may serve to hold the segments in position upon the track bars until they are discharged over the ends of the 130

latter at the rear or tail end of the machine.

The saws 74 may, when desired, be adjusted upon the shafts or mandrels, longitudinally of the axes of the latter, in order to enable segments or blanks of various lengths to be operated upon. It will be noticed that blanks or segments, greatly varying in length, may be efficiently operated upon by this machine owing to the fact that the track bars which constitute the bed over which the segments are guided are adjustable toward and away from each other, thus enabling them to be so adjusted as to support the blanks or segments near the ends of the latter where they are subjected to the strain of the saws; the material that is to be operated upon will thus be very firmly and securely supported under all circumstances.

20 When the track bars are moved apart from each other, for the purpose of supporting blanks or segments of considerable length, the inner ends of the saw carrying mandrels will be simultaneously moved in an upward direction, and the saws will thus be moved upwardly together with the track bars so as to occupy approximately the same relative position to the track bars which is obviously desirable in order to enable the mitering to be performed at all circumstance without exposing a considerable portion of the saws to frictional contact with the ends of the material that is being cut.

The general construction of the machine is simple, and the component parts are so arranged and assembled as to be under convenient control of the operator.

Having thus fully described the invention, what I claim is:—

40 1. In a machine of the class described, a stationary frame, a vertically adjustable frame, saw carrying mandrels each supported in pivoted bearings upon the stationary and adjustable frames respectively, and work supporting members and an endless feed element carried by the adjustable frame.

2. In a machine of the class described, a stationary frame, a vertically adjustable frame, saw carrying mandrels each supported in pivoted bearings upon the stationary and movable frames respectively, track bars supported longitudinally upon the vertically adjustable frame, and an endless feed element carried by the latter frame.

3. In a machine of the class described, a stationary frame, a vertically adjustable frame, saw carrying mandrels each supported in pivoted bearings upon the stationary and adjustable frames, respectively, laterally adjustable track bars supported upon the vertically movable frame, and an endless feed element carried by the latter frame.

4. In a machine of the class described, a

stationary frame, a vertically movable frame, saw carrying mandrels each supported in pivoted bearings upon the stationary and movable frames respectively, vertically adjustable track bars supported upon the movable frame and an endless feed element carried by the latter frame.

5. In a machine of the class described, a stationary frame, a vertically movable frame, saw carrying mandrels each supported in pivoted bearings upon the stationary and movable frames respectively, laterally and vertically adjustable track bars supported upon the movable frame, and an endless feed element carried by the latter frame,

6. In a machine of the class described, a stationary frame, a vertically movable frame, saw carrying mandrels each supported in pivoted bearings upon the stationary and movable frames respectively, laterally adjustable slides supported upon the movable frame, vertically movable members guided through the slides, longitudinally disposed track bars connected with the vertically movable members, and an endless feed element carried by the movable frame.

7. In a machine of the class described, a stationary frame, a vertically movable frame, saw carrying mandrels each supported in pivoted bearings upon the stationary and movable frames respectively, laterally movable slides guided upon the movable frame, vertically movable members guided through the slides, longitudinally disposed track bars carried by the vertically movable members, a feed element carried by the movable frame and a brush member carried by said frame, suspended adjustably above the feed element.

8. In a machine of the class described, a stationary frame having transverse rock shafts provided with bell-cranks, a link connecting said cranks, arms radiating from the rock shafts, a vertically movable frame connected pivotally with said arms and counterweighted arms extending from the rock shafts, laterally and vertically adjustable track bars supported by the adjustable frame, an endless feed element carried by the latter, a driven shaft supported by the stationary frame, means for transmitting motion from said driven shaft to the feed element, saw carrying mandrels each supported in pivoted bearings upon the stationary and adjustable frames respectively, and means for transmitting motion from the driven shaft to the saw carrying mandrels.

9. In a machine of the class described, a stationary frame, a vertically adjustable frame, track bars supported adjustably by the adjustable frame, an endless feed element carried by the latter frame, said feed element including links having beveled edges and upstanding transverse flanges, means

upon the adjustable frame for guiding the beveled edged links of the feed element, and saw carrying mandrels each supported in pivoted bearings upon the stationary and adjustable frames, respectively.

10. In a machine of the class described, a stationary frame, a vertically adjustable frame, longitudinally disposed track bars supported adjustably upon the adjustable frame, a brush member supported adjustably above the track bars and having downward extending resilient flexible tongues, an

endless feed element operating between the track bars, adjustably supported saw carrying mandrels having saws disposed adjacent 15 to the track bars, and bearings for the inner ends of said mandrels connected hingedly with the vertically adjustable frame.

In testimony whereof, I affix my signature in presence of two witnesses.

HENRY J. BUCKEL.
